UNITED STATES PATENT OFFICE

OTTMAR CONRADTY, OF NUERMBERG, GERMANY

ARC LAMP

Application filed November 18, 1930, Serial No. 496,414, and in Germany November 18, 1929.

My invention relates to improvements in arc lamps, and more particularly in arc lamps used in therapeutics and comprising a reflector, carbon electrodes within said reflector and series resistances. In systems of this type the series resistances have been disposed internally of the reflector so that the energy taken up by the said resistances is used for radiation. In such constructions the dimension of the resistances must be small, so that in the operation of the radiation system the resistances are heated more or less to red heat. The large amount of heat which is thus produced is reflected together with the light rays, which is desirable for the reason that the said heat rays have a beneficent physiological and psychological influence. However, the heat radiation of the said resistances which by reason of their small dimensions are heated to red heat is too high, and after a short time of treatment the patient must be removed from the field of radiation because otherwise he would be endangered by the heat. Therefore either radiation must be interrupted or the distance between the lamp and the patient must be enlarged. The enlarging of the said distance is objectionable for the reason that the efficiency of the ultra-violet rays is rapidly reduced as the distance between the patient and the source of radiation is increased. Therefore, if the source of radiation is located a large distance away from the patient, the radiation is weakened or made ineffective. The heat rays are perceived even if they are located a great distance away from the patient, who therefore has the impression of an effective radiation, while as a matter of fact there is no radiation effect. The object of the improvements is to provide a system in which a part or all of the heating power of the resistances is made use of in which however the heat radiation of the said resistances is reduced so far that it is not objectionable; and with this object in view I dispose the resistances on the outside of the reflector and so that its heat is transmitted to the metallic body of the reflector thus heating the same and causing the same to emanate heat rays which are pleasing to the pa-

tient without interfering with the proper function of the apparatus, the said apparatus being located at the normal distance away from the patient.

For the purpose of explaining the invention several examples embodying the same drawing, in which

Fig. 1 is an elevation showing the reflector and the casing enclosing the same,

Fig. 2 is a sectional elevation taken on the line 2-2 of Fig. 1,

Fig. 3 is a similar sectional elevation showing the reflector moved forwardly and out of the casing enclosing the same,

Fig. 4 is an elevation similar to the one illustrated in Fig. 1 and showing the reflector retracted from the casing, and

Fig. 5 is an elevation showing a modification.

In the construction shown in Figs. 1 to 3 the metallic reflector *a* is disposed within a casing *c* having its front part made concave to accommodate the reflector. Within the reflector there are carbons shown conventionally at *e*, and the reflector is mounted on a link *d* jointed to the bottom part of the casing *c* at *f* and permitting the reflector to be moved from the position shown in Fig. 2 outwardly and into the position shown in Fig. 3. The regulating resistances *b* are disposed outside the reflector *a* and within the casing *c* around the reflector so as to transmit the heat produced therein to the reflector. But the resistance may also be placed within the casing at opposite sides of the reflector, as is shown in Fig. 5.

In the operation the apparatus is used either in the position of the reflector *a* shown in Fig. 2, or in the position of the reflector shown in Fig. 3 or with the reflector in an intermediate position, the said reflector being retracted from the casing more or less according to the desired degree of the heat. The reflector will be retracted from the casing *c* if increased heat radiation is unpleasant to the patient or undesirable for therapeutic reasons.

While in describing the invention reference has been made to a particular example embodying the same. I wish it to be understood that my invention is not limited to the con-

struction shown in the figures and that various changes may be made in the general arrangement of the apparatus and the construction of its parts without departing from the invention. For example, instead of disposing the resistances *b* within a casing *c* and on either side of the reflector, they may be coiled around the body of the reflector *a*. Further, instead of mounting the body of the reflector *a* on a rockable arm *d* it may be slidably supported in suitable guide ways.

I claim:

1. A therapeutical lamp, comprising supporting-means, arc-electrodes therein, a reflector therefor, and a variable resistance mounted on said supporting-means, rearwardly of the reflector for heating the reflector, said reflector being movably mounted upon and connected to said support for swinging movement toward and away from the same and the resistance to vary the heating effect thereby.
2. A therapeutical lamp, comprising a casing with a concave front, a reflector fitted into said concave front part of the casing, a variable resistance located on the casing in a position for directly heating the reflector, and means for supporting and connecting the reflector so that it can be swingably protruded from the casing and swingably retracted into the casing.

In testimony whereof I hereunto affix my signature.

OTTMAR CONRADTY.
